UNITED STATES PATENT OFFICE.

BLANCHE DE PINNA LEMAN, OF WHITE PLAINS, NEW YORK.

COMBINATION-GARMENT.

1,102,520.

Specification of Letters Patent.

Patented July 7, 1914.

Application filed October 31, 1912. Serial No. 728,962.

To all whom it may concern:

Be it known that I, BLANCHE DE PINNA LEMAN, a citizen of the United States, residing at White Plains, in the county of 5 Westchester and State of New York, have invented certain new and useful Improvements in Combination-Garments; and I do declare the following to be a full, clear, and exact description of the invention, such as 10 will enable others skilled in the art to which it appertains to make and use the same.

This invention relates to an improved union garment.

The object of the invention is to provide 15 a union garment composed of a knit fabric body portion and a cloth or other inelastic fabric lower portion in the form of drawers.

With this and other objects in view, the invention consists of certain novel features 20 of construction, combination and arrangement of parts, as will be more fully described and claimed.

In the accompanying drawings; Figure 1 represents a front elevation of one form of 25 this invention with the leg portions spread apart to show the connection; Fig. 2 is a perspective view of the form shown in Fig. 1, taken from the lower end; Fig. 3 is a front elevation of another form of the invention with the division strip in inoperative 30 position; Fig. 4 is a perspective view taken from the lower end of the garment shown in Fig. 3 with the parts in operative position; Fig. 5 is a central longitudinal 35 section of the form shown in Figs. 3 and 4, with the parts in operative position.

In the embodiment illustrated in Figs. 1 and 2, the body portion 1 of the garment is shown in the form of a knit undervest or 40 shirt of what is known as three quarter length and to the lower edge of which are secured two straight pieces in the form of frills joined to form leg portions 2 and 3, being connected together at their upper 45 edges for a short distance as shown at 2^a, said connected portion being arranged at a point midway the width of the body portion 1 extending transversely between the front and rear portions thereof and forming 50 a divided skirt, the lower edge of the knit tubular body portion being preferably stretched when the strips or frills forming the leg portions 2 and 3 are being stitched thereto to provide full leg portions or skirt 55 members.

The upper edges of the leg portions 2 and

3 are stitched together as shown at 2^a in Fig. 2 and are of a sufficient length to properly space the front and back of the garment and adapt it to comfortably fit the wearer. 60 This arrangement provides a garment in which the knit portion is held down in proper position and large, cool drawer legs are provided which, being made of cotton or other non-elastic material, do not cling 65 or adhere to the limbs of the wearer as do the leg portions of knit fabric garments.

In the form shown in Figs. 3 and 4, the leg or skirt portion is formed from a continuous straight strip or frill of material 4 70 of greater length than the width of the body portion 1, two pieces being here shown stitched together to form this strip but it is obvious it may be made from a single strip of material when convenient, and is 75 stitched at its upper edge to the lower edge of said body portion forming a seam 1^a, and the upper edges of the projecting ends 5 and 6 of this strip which are preferably disposed midway the width of the back of 80 the garment are stitched together as shown at 5^a and the terminals 5' and 6' of said ends are also stitched together in a plane at right angles to the upper edges. The connected terminals of the ends 5 and 6 are 85 provided at their upper ends with a fastening element preferably in the form of a button-hole 7 which is adapted to engage a suitable button 8 arranged on the inner face of the garment midway the width of the front of 90 the garment at the seam 1^a, which joins the frill or strip 4 to the lower portion of the body 1, whereby the legs 9 and 10 of the drawers are formed and the front and rear portions of the garment spaced a suitable 95 distance apart to produce a comfortable fit, and when the fastening elements are disengaged the garment may be easily washed and ironed.

While I have described my invention with 100 more or less minuteness as regards details and as being embodied in certain precise forms, I do not desire to be limited thereto unduly any more than is pointed out in the claims. On the contrary, I contemplate all 105 proper changes in form, construction and arrangement, the omission of immaterial elements and substitution of equivalents as circumstances may suggest or render expedient.

What is claimed is:—

1. A combination garment comprising a

tubular knit fabric body portion, and drawer legs of inelastic material secured to the lower edge of said body portion, each leg being wider than one-half of the width of the tubular body portion at its lower edge, said legs being connected together at their adjacent upper edges between the front and rear of the body portion of the garment.

2. A combination garment comprising a tubular knit fabric body portion, and drawer legs of inelastic material secured to the lower edges thereof, each of said legs being composed of a strip of material of a length greater than one-half of the width of the body portion of the garment at its lower edge, said leg portions being connected together at their adjacent upper edges at a point midway the width of the body portion.

3. A combination garment comprising a

tubular knit fabric body portion having a strip stitched at one edge to the lower edge of said garment, said strip being of greater length than the circumference of the lower edge of the garment thereby providing projecting ends which are arranged intermediate of the width of the garment, said projecting ends being secured together at their upper edges, and means for detachably connecting the terminals of said connected ends to the garment at a point opposite the side of the garment from which they project.

In testimony whereof I have hereunto set my hand in presence of two subscribing witnesses.

BLANCHE DE PINNA LEMAN.
